UNITED STATES PATENT OFFICE

GABRIEL LOWENSTEIN, OF NEW YORK, N. Y., ASSIGNOR TO FRED FEAR & CO., OF BROOKLYN, NEW YORK, A CORPORATION OF NEW YORK

DESIGN FOR AN EASEL

Application filed December 5, 1930. Serial No. 37,889. Term of patent 14 years.

To all whom it may concern:

Be it known that I, GABRIEL LOWENSTEIN, a citizen of the United States, residing in New York city, county of New York, and State of New York, have invented a new, original, and ornamental Design for an Easel, of which the following is a specification, reference being had to the accompanying drawing, forming part thereof.

Figure 1 is a front elevational view of an easel showing my new design;

Figure 2 is a top plan view of the easel slightly tilted forward; and

Figure 3 is a side elevational view thereof.

I claim:

The ornamental design for an easel, as shown.

In testimony whereof I have hereunto set my hand on this 1st day of December, A. D. 1930.

GABRIEL LOWENSTEIN.
